UNITED STATES PATENT OFFICE.

JESSE SYLVESTER ANDERSON, OF MADISON, NEW JERSEY.

DESIGN FOR A PLAQUE.

Application filed September 11, 1928. Serial No. 28,113. Term of patent 3½ years.

To all whom it may concern:

Be it known that I, JESSE SYLVESTER ANDERSON, a citizen of the United States, residing at Madison, county of Morris, and State of New Jersey, have invented a new, original, and ornamental Design for Plaques, of which the following is a specification, reference being had to the accompanying drawing, forming a part thereof.

I claim:

The ornamental design for a plaque, as shown.

JESSE SYLVESTER ANDERSON.
